[57] CLAIM

The ornamental design for a modular lamp stand for indirect lighting, substantially as shown and described.

DESCRIPTION

FIG. 1 is a perspective view of a modular lamp stand for indirect lighting as viewed from the front side showing our new design;

FIG. 2 is a perspective view thereof as viewed from the rear side;

FIG. 3 is a front elevational view thereof;

FIG. 4 is a right side elevational view thereof, the left side being identical with the right side;

FIG. 5 is a rear elevational view thereof;

FIG. 6 is a top plan view thereof; and

FIG. 7 is a fragmentary top perspective view thereof.
